UNITED STATES PATENT OFFICE

EMIL P. BUTUSOV, OF HOLLYWOOD, ILLINOIS, ASSIGNOR OF ONE-HALF TO DANIEL LEWY, OF CHICAGO, ILLINOIS

ELEVATOR SIGNALING SYSTEM

Application filed March 19, 1926. Serial No. 95,999.

This invention relates to elevator signaling systems employing electric signals upon different floors controlled by prospective passengers and employed to inform the signaling passengers of the approach of the elevator cars to their floors, there usually being employed electric signal devices in the elevator cars which are caused to respond when the signal devices upon the floors respond.

10 The invention has for its primary object the simplification and improvement in the equipment and wiring employed in such a system.

Another object of the invention is to provide a plurality of central relays corresponding in number to the number of elevator cars in service in the building, these central relays being placed in a central cabinet situated on a floor centrally disposed with respect to 20 the floors traversed by the elevator cars with the object of effecting a great saving in wiring from the mechanically operated elevator mechanism to the electromagnetically operated mechanism in the central cabinet and 25 from the central cabinet to the signals on the various floors to be served.

This application forms a continuation in part of application Serial Number 331,116, filed October 16, 1919, for an elevator signal- 30 ing system.

The essential features of this invention for which broad protection is sought are pointed out and claimed in the annexed claims. The essential mechanical and electrical features 35 disclosed herein and their method of operation are claimed in the copending application Serial Number 331,114, filed October 16, 1919, now Patent Number 1,581,383, patented April 20, 1926.

40 Prior to this invention in all elevator signaling systems employing a plurality of cars serving a building having a great number of floors, great difficulty has been experienced in running the necessarily large number of 45 electrical conductors from the various controlling units to the signals to be controlled. In a large office building, the amount of wiring, that is, the complicated wiring connecting the individual electrical units forming 50 the system runs into many miles of conductor

and the many wiring difficulties arising in such a situation are too numerous to mention. The cost of the conductors alone becomes a serious problem. Furthermore, in the event that the system fails to function properly, "trouble shooting" as it is commonly termed becomes very difficult and it is not uncommon to find elevator systems frequently out of commission for long periods of time, simply because the trouble cannot be located immediately. 55

By employing the method of wiring up or electrically connecting the various units set forth in the present invention together with the simple grouping of all vital units at one central point, the many annoying problems heretofore experienced are almost entirely obviated and certainly it will be apparent that the original installation cost of the system will be greatly reduced over that in prior 70 systems. 65

The various central relays for the entire system may be interlocked by connecting them in multiple, thereby causing all of the signals for all of the elevator cars to function even though one car alone is in operation. Since all of the central relays are situated at one point, all of the wipers, contacts, push-button relays and the electromagnetic mechanism for operating the wipers can be mounted in 75 a cabinet at the factory where all the complicated wiring can be completed and thence transported to the building and installed on the desired floor. This method of installation obviates all of the complicated, exceedingly long lengths of wiring formerly necessary since it is only required to run a few wires from the switching mechanism of each elevator to the cabinet and from the cabinet to the signals or lights on the various floors. 80

85 The invention will be fully explained by reference to the accompanying drawings showing the preferred embodiment of the invention:—

Figure 1 illustrates a wiring diagram for 90 a complete installation of the signaling system for one elevator car serving four floors of a building;

Figure 2 is a sectional elevation of a multi-story building having in operation a plurality 95 100

of elevator cars and shows the preferred method of installing the system with respect to the pent-houses and the central cabinet; and

5 Figure 3 shows the central cabinet per se containing the vital electrical units of the system shown in conventional style only.

Since each elevator car employs the same 10 signaling system and since all of the systems are interlocked, reference will be made to the operation of the system of one car only, as all of the other cars will operate in the same manner.

The drawing of Figure 1 illustrates one set 15 of up signals 1, 2 and 3, located respectively upon the first, second and third floors, these up signals being desirably in the form of white incandescent lamps. A set of down signals 4, 5 and 6 are located respectively 20 upon the fourth, third and second floors. These signals serve to inform signaling passengers of the approach of the elevator cars to their floors. Up push buttons or switches 7, 8 and 9 are respectively upon the first, second and third floors and respectively in 25 controlling relation to the up signals 1, 2 and 3 upon these floors. Down push buttons or switches 10, 11 and 12 are respectively upon the fourth, third and second floors and respectively in 30 controlling relation to the down signals 4, 5 and 6 upon these floors. These push buttons are respectively individual to the self-locking electro-magnets 13, 14, 15, 16, 17 and 18 that are partially controlled 35 thereby and whose armature switches are serially included in the respective circuits of said signals. The elevator system operates a down wiper or contact member 19 and an up wiper or contact member 20, wiper 19, 40 when suitably positioned by the elevator system, co-operating with the down push buttons 11 and 12 and the up push button 7 in the display of the signals 5, 6 and 1 individual to those push buttons while the up wiper 45 20, when suitably positioned by the elevator system, co-operates with the up push buttons 8 and 9 and the down push button 10 in the display of signals 2, 3 and 4. When the down wiper 19 functions it turns counter-clockwise and when the up wiper 20 functions it turns clockwise. These wipers perform their functions through waiting contacts successively reached thereby in proper time with respect to the position 50 of the elevator car. These waiting contacts comprise waiting terminals of the signal lamps the first floor having a waiting contact 21 engaged by the down wiper 19 when the elevator car is near or in its down position. As the elevator car moves upwardly and has reached its proper positions in advance of the floors where the signals are to be displayed, it successively encounters the waiting contacts 22 and 23 constituting 55 the waiting terminals of the up sig-

nals 2 and 3 and finally encounters the waiting contact 24, when sufficiently near the top floor, to light the down signal 4. It is understood that none of these up or down signals are lighted, however, unless the push button or push buttons corresponding thereto are depressed.

The elevator attendant is apprised of the fact that passengers wish to enter his car A by the illumination of either the up signal 26 or the down signal 27 located upon the car. This down signal 27 is controlled by a down wiper 28 engageable with the waiting contacts 29 and 30 that individually pertain to the down signals 5 and 6 and the waiting contact 31 pertaining to the up signal 1, the down wiper 28, similarly to the down wiper 19, being effective when moving counter-clockwise and in such movement encountering its waiting contacts in the order of their enumeration. The up signal 26 is controlled by an up wiper 32 engageable with the waiting contacts 33 and 34 that individually pertain to the up signals 2 and 3 and the waiting contact 35 pertaining to the down signal 4, the up wiper 32, similarly to the up wiper 20, being effective when moving clockwise and in such movement encountering its waiting contacts in the order of their enumeration.

When any push button is depressed, as for example the push button 7, circuit is established therethrough, traceable from the right hand terminal of the battery 25, the magnet 13 for the push button 7 individual to the push button, thence to the left hand terminal of the battery whereafter the actuated push button may be immediately released as the armature of the energized magnet is caught and held by the armature of a restoring or releasing magnet, the magnets 13 to 18 inclusive, having releasing or restoring magnets 36, 37, 38, 39, 40 and 41, respectively individual thereto.

Let it be assumed that some push button, say the second floor push button 8, has been depressed, the magnet of such push button, the magnet 14 in the case of push button 8, is energized and the armature switch thereof illustrated at the left side of its armature is closed and maintained closed owing to the locked position of such armature. When the wipers pertaining to the energized magnet, the wipers 20 and 32 in the example taken, have been caused to reach the waiting contacts 22 and 33 by the mechanism actuated by the elevator system, as will more fully appear, the second floor signal 2 corresponding to the push button 8 and the magnet energized due to the depression of such button will be displayed as will also the corresponding signal upon the elevator car. The circuit of the second floor signal 2 is traceable from the right hand terminal of the battery 25, through the switch 42 upon the car A and which is placed in a set closed position by the

operator at the beginning of his work, the master switch 43 which is adjusted by the elevator system through mechanism to be described, to connect the up wipers in circuit 5 when the car has reached its lower limit or goes up and to connect the down wipers in circuit when the car has reached its upper limit or goes down, the conductor 44, common to the signals 2, 3 and 4, the signal 2, the 10 waiting contact 22 pertaining to this signal, the up wiper 20 the up wiper 32, the waiting contact 33 pertaining to the up wiper 32, the armature switch of the actuated magnet 14 shown at the left of this magnet, to the left hand terminal of said battery. The signal at this time displayed upon the car A is the signal 26 whose circuit is traceable from the right hand terminal of the battery 25, through the signal 26, the up 15 wiper 32, the waiting contact 33, the armature switch of the energized magnet 14, to the left hand terminal of said battery.

The master switch 43 is shifted to its alternative positions by means of the Geneva gearing 45 that operates an arm 46 in oscillating relation to said switch. A suitable time after their occurrence the signals displayed upon the floor and upon the car are cancelled. To this end there is employed an up wiper 20 20 47 which turns clockwise when effective and successively engages waiting contacts 48, 49 and 50 that are respectively employed for cancelling the signals manifested by the up signal devices 2 and 3 upon the second and 25 30 third floors and the down signal device 4 upon the top floor. A down wiper 51 which turns counterclockwise when effective successively engages waiting contacts 52, 53, and 54 that are respectively employed for cancelling the signals manifested by the down signal devices 5 and 6 upon the third and second floors and the up signal 1 upon the first floor. In the case of the supposedly energized magnet 14, the signal conveyed by the signal device 2 is subsequently effaced upon the energization of the releasing magnet 37 whose circuit is traceable from the right hand terminal of battery 25, through the master switch 43, the up wiper 47 (the master switch 35 40 45 50 55 60 65 70 75 80 85 90 95 100 105 110 115 120 125 130 135 140 145 150 155 160 165 69, the segment 66, the contact ring 72, the brush 75, the magnets 57 and 56 in series, the brush 76, the ring 73, the contact segment 67, the brush 70, to the battery 25. At this time circuit through the magnet 58 is open at the segment 68. When the brush 69 is engaged by the segment 67, circuit is established which is traceable from the battery 25, through the brush 69, the segment 67, the contact ring 73, the brush 76, the magnets 56 and 58 in series, the brush 74, the ring 71, the contact segment 68, the brush 70, to the battery 25. At this time circuit through magnet 57 is open at the segment 66. When the brush 69 is engaged by the segment 68, circuit is established which is traceable from the battery 25, through the brush 69, the segment 68, the contact ring 71, the brush 74, the magnets 58 and 56 in series, the brush 76, the ring 73, the contact segment 67, the brush 70, to the battery 25. At this time circuit through magnet 56 is open at the segment 67. The shaft 55 will thus turn clockwise. If the ring 66, 67 and 68 is turning clockwise, it will be apparent that the shaft 55 will be turning counter-clockwise.

The foregoing description applies to the complete system for use with one elevator car. Since there are a plurality of elevator cars disclosed, each employing the same system, it is intended to connect the systems in multiple, or in other words, to interlock them. This method of interlocking is shown clearly in Figures 2 and 3, wherein two elevator systems are interlocked and the number of elevators that can be so interlocked is governed only by the size of the building to be served, there being no theoretical limit.

Referring to Figure 2, F_1 , F_2 , F_3 and F_4 represent the various floors of a building served by the cars A and B. The car-operated switches, as hereinbefore described, are mounted in the pent-house P at the top of the hatchway. The central cabinet 77 is situated on floor F_3 , intermediate of the floors traversed and contains all of the wiper shafts, electromagnets, contacts, releasing magnets and the complicated wiring for these various parts.

From a study of Figure 2, it will be seen that the hatchway contains only a few runs of conductor cable, leading from the pent-house switching mechanism to the central cabinet. All of the complicated wiring is in the cabinet and is removed entirely from the hatchway. From the cabinet, wires can be led to the signals and push buttons on the individual floors. It will be readily appreciated that many miles of conductor are saved in a building of a moderate size operating a plurality of elevators. The wiring from the pent-house to the central cabinet is relatively simple. Experience has proved that it is the wiring which is placed in the central cabinet, which heretofore has been

placed in the hatchways, that generally causes trouble in operation. As the system grows, with the size of the building, these troubles increase.

Figure 3 shows the central cabinet or "wired" cabinet 77 in sectional elevation with the various electrical units therein shown in conventional form only as it would obviously be impossible to show the parts in their true form in a complicated interlocked system. The parts shown represent those necessary for a two car system and it is just as easy in commercial installations to place the parts necessary for a twelve car system in the cabinet as it is to place them there for a two car system. The systems are interlocked by conductors 78, 79, 80, 81, 82 and 83 connecting the wipers on the wiper shafts 55 and 55. All of the wiper shafts and the waiting contacts are grouped in one section of the cabinet and the many electromagnets and releasing electromagnets are mounted in another section of the cabinet. As shown in the drawings, all of the up electromagnets for elevator Number 1 are mounted in one vertical row and all of the down electromagnets for the same elevator are mounted in another vertical row. The same method of grouping is followed out for each successive elevator added to the system.

The wiring necessary for all of these parts can be of smaller size than would be required if the wires were placed in the hatchway because they are not subjected to severe operating conditions. A very great advantage also accrues from the fact that this complicated wiring can be done in the shop when the parts are mounted in the cabinet and far better work can be done than when the individual parts are assembled on the construction job. When the wired cabinet arrives at the building for installation, only the few external wires already mentioned need be connected to the cabinet.

Another decided advantage of this method of installation resides in the ease with which "trouble-shooting" can be accomplished. The repair-man need only open the door of the cabinet and there he will find all of the vital and delicate electrical equipment before him. He can test each relay by itself or test all of them collectively. The time necessary for this work is thereby reduced to a minimum since everything is grouped at one central point. The mechanically actuated selecting means in the pent-house seldom is the cause of any trouble but experience shows that the electrically actuated means is the principal cause of trouble. Other important advantages accruing from the method of wiring the signal system disclosed herein will present themselves to those skilled in the art.

I claim:—

1. An elevator signaling system for an elevator system including a plurality of cars

each serving a plurality of floors, signals individual to each of said cars, circuits for said signals, passenger controlled means at each floor for preparing said circuits including relays, electromagnetically operated selecting switches one for each car for completing said signal circuits, a panel located at a centralized location with respect to said cars and mounting all of the relays and selecting switches thereon, and means individual to each of said cars and mechanically operated by movements of the associated car up and down its shaft for correspondingly operating the selecting switch whereby the circuits prepared by the passenger controlled means will be completed upon the approach of the car to the floor from which the passenger controlled means has been operated.

5   said signal circuits, a panel located at a centralized location with respect to said cars and mounting all of the relays and selecting switches thereon, the selecting switches and relays pertaining to an individual car being 70 interconnected with the corresponding selecting switches and relays of every other car in said system and means individual to each of said cars and mechanically operated by movements of the associated car up and down 75 its shaft for correspondingly operating the selecting switch whereby the circuits prepared by the passenger controlled means will be completed upon the approach of the car to the floor from which the passenger controlled 80 means has been operated.

In testimony whereof I affix my signature.
EMIL P. BUTUSOV.

20   2. An elevator signaling system for an elevator system including a plurality of cars each serving a plurality of floors, up-signals and down-signals individual to each of said cars, circuits for said signals, push-button switches at each floor for preparing said circuits including relays, electromagnetically operated selecting switches one for each car for completing said signal circuits, a panel located at a centralized location with respect to said cars and mounting all of the relays 25 and selecting switches thereon and means including a commutating device individual to each of said cars and mechanically operated by movements of the associated car up and down its shaft for correspondingly operating the selecting switch whereby the circuits prepared by the push-button switches will be completed upon the approach of the car to the floor from which the push-button switch has been operated.

30   3. An elevator signaling system for an elevator system including a plurality of cars each serving a plurality of floors, signals individual to each of said cars, circuits for said signals, passenger controlled means at each floor for preparing said circuits including relays, electromagnetically operated selecting switches one for each car for completing said signal circuits, means for operating said selecting switches by, and in accordance with, the movements of said cars, and a panel located at a centralized location with respect to said cars and mounting all of the relays and selecting switches thereon, the selecting switches and relays pertaining to an individual car being interconnected with the corresponding selecting switches and relays of every other car in said system.

40   4. An elevator signaling system for an elevator system including a plurality of cars each serving a plurality of floors, signals individual to each of said cars, circuits for said signals, passenger controlled means at each floor for preparing said circuits including relays, electromagnetically operated selecting switches one for each car for completing
